Primary Examiner—Alan P. Douglas*Assistant Examiner*—S. Snapp*Attorney, Agent, or Firm*—Michael Sand Co.[57] **CLAIM**

The ornamental design for a compact disc storage container, as shown and described.

DESCRIPTION

FIG. 1 is a perspective view of a compact disc storage container;

FIG. 2 is a front elevational view thereof;

FIG. 3 is a right side elevational view thereof, the left side being a mirror image;

FIG. 4 is a top plan view thereof;

FIG. 5 is a bottom plan view thereof;

FIG. 6 is a rear elevational view thereof;

FIG. 7 is a perspective view similar to FIG. 1 of a modified embodiment of the compact disc storage container having a closure door shown in partially open position; and,

FIG. 8 is a perspective view of the embodiment of FIG. 7 with the door shown in closed position.
